UNITED STATES PATENT OFFICE

2,034,827

CIRCUIT BREAKER

Joseph A. O'Brien, Baltimore, Md.

Application January 10, 1934, Serial No. 706,111

1 Claim. (Cl. 200—116)

This invention appertains to new and useful improvements in the general art of circuit makers and breakers, and more particularly to a novel circuit breaker which has as its principal object to provide a thermal trip mechanism which will operate under any conditions on an electrical circuit, such as an overload or short circuit, to instantaneously open the circuit.

Another important object of the present invention is to provide a circuit breaker which is enclosed in a casing and suitably sealed so that the thermal element cannot be tampered with.

Another important object of the invention is to provide a circuit breaker which is substantially fool-proof.

Still another important object of the present invention is to provide a switch wherein the thermal circuit breaker operates even if the switch control is retained manually in closed circuit position.

Another important object of the present invention is to provide a switch wherein indicating means is provided for indicating when the thermal circuit breaker has been operated.

Another important object of the present invention is to provide a switch including a thermal circuit breaker which can be re-set by moving the switch handle from the "On" position to the "Off" position.

Various other important objects and advantages of the invention will become apparent to the reader of the following specification.

In the drawings:—

Figure 1 represents a front elevational view of the encased switch, with the handle in "On" position and the re-set indicator blank.

Figure 2 represents a front elevational view of the encased switch, showing the re-set indicator indicia exposed.

Figure 3 represents a longitudinal sectional view taken substantially on line 3—3 of Figure 2.

Figure 4 represents a longitudinal sectional view also taken on line 3—3 of Figure 2, but showing the thermal breaker operated.

Figure 5 represents a longitudinal sectional view through the switch mechanism, showing the switch mechanism in closed position.

Figure 6 represents a longitudinal sectional view through the switch mechanism, showing the circuit breaker operated by the thermal element.

Figure 7 represents a longitudinal sectional view through the switch mechanism, showing the switch means in circuit open position by manual control.

Figure 8 represents a side elevational view of the thermal element.

Figure 9 represents a fragmentary detailed sectional view taken substantially on line 9—9 of Figure 8.

Figure 10 represents an enlarged fragmentary detailed sectional view taken substantially on line 10—10 of Figure 1.

Figure 11 represents a perspective view of the trip arm.

Figure 12 represents a perspective view of the carrier plate.

Figure 13 represents a perspective view of the trip throwing member.

Figure 14 represents a perspective view of the swingable contact plate.

Figure 15 represents a perspective view of the trigger arm.

Figure 16 represents a perspective view of the bell crank.

Figure 17 represents a perspective view of the indicator operating arm.

Figure 18 represents a front elevational view of a modified form of switch including an indicating lamp.

Figure 19 represents a front elevational view of the switch mechanism, with the cover plate removed.

Figure 20 represents a side elevational view of the mechanism in the casing shown in Figure 19, with the thermostatic circuit breaker operated.

Figure 21 represents a perspective view of the contact arm for the indicator lamp of this modified form of the switch.

Referring to the drawings wherein like numerals designate like parts, it can be seen that numeral 5 represents the base of the switch which can be of any suitable di-electric material. Numeral 6 represents a hood for disposition over the mechanism of the switch and this hood is provided with suitable means whereby the same can be secured to the base, but as is clearly shown in Figure 10, it is preferred that the bottom of the base 5 be provided with recesses and that screws 8 be disposed through the base and fed into the edge portion of the hood 6 so that the heads of the screws will be located within the recesses. These recesses are then filled with some suitable sealing material 9 so that access cannot be had to the mechanism contained in the hood.

The hood 6 is provided with a slot 10 therein through which the handle 11 of the switch lever 12 can protrude, this handle 11, being of suitable di-electric material. The lever 12 carries a

curved plate 13 which always maintains the slot 10 closed.

In carrying out the present invention, the switch proper is of the quick-throw, spring toggle type and consists of a plate 14 having a pair of posts 15-15 extending upwardly from one end thereof, while a pair of posts 16 extends upwardly from the opposite end of the plate.

Numeral 17 represents an L-shaped contact post at one end of the base 5, which affords an obliquely disposed contact member 18 complementary to the obliquely disposed contact 19 on one end of the swingable contact plate 20. A shoulder 21 is formed by offsetting the contact 19 with respect to the plate 20 and in this shoulder 21 is the opening 22 for the latch projection 23 on the offset extension 24 of the trip arm 25 at the opposite end of which a longitudinally extending slot 26 is provided.

The swingable contact plate 20 is provided with a pair of laterally extending lugs 27-27 projecting from opposite edges of the plate adjacent the shoulder 21 and each is provided with an opening 28 therein for receiving one end of a spring, only one spring being shown in the drawings and this is denoted by numeral 29. The spring connects at one end to the corresponding lug 27 and at its opposite end to the lug 30 protruding from the plate 14. (See Figure 4.)

A pair of upstanding ears 31-31 is provided at the remaining end of the plate 20 and these have openings 32 therein through which the pin 33 extends, this pin 33 extending through the posts 16 and also through the openings 34 in the ears 35-35 at one end of the aforementioned carrier plate, generally referred to by numeral 36. Thus the carrier plate 36 and the swingable contact plate 20 are carried by the aforementioned pin 33. The adjacent end of the carrier plate 36 is slotted, as at 37, to receive the inner end of the trigger arm 38 and apertured ears 39 at this end of the carrier plate 36 support a pin which also extends through the opening 40 at the inner end of the arm 38 so that the arm 38 is swingably carried by the carrier plate 36. It will also be observed that the corresponding end of the contact plate 20 has a cut-out, denoted by numeral 41, for accommodating the action of the slotted end of the carrier plate 36.

As is clearly shown in Figures 5, 6 and 7, a short strip spring 42 is carried by the bottom of the carrier plate 36 and this tensionally bears against the toe 43 at the pivotal end of the trigger arm 38 so as to normally throw the same tensionally against the trip arm 25 at the outer end of the slot 26 through which the same operates. It will also be observed that the trigger arm 38 has a shoulder 44 at an intermediate point under which the free end of the trip arm 25 can engage, and also a laterally disposed head 45 at its free end which is located within the path of the insulated head piece 46 on the outer end of the U-shaped bi-metal thermal element 47. The leg portions of this thermal element have 65 feet 48-49, one of which is connected to the binding post 50, while the other is connected by the jumper 51 to the adjacent end of the carrier plate 36. (See Figure 4.)

The other end of the carrier plate 36 is provided with a pair of upstanding hook-shaped members 52 bridged by a member 53. As is clearly shown in Figure 4, the extension 24 of the trip arm 25 extends through the space between the bridge piece 53 and the adjacent end 75 of the carrier plate 36.

The trip throwing member is denoted by numeral 54 and is a channel iron shaped structure having registering openings 55 in its side flanges and a pair of oppositely directed leg members 56 at its opposite end. A portion of the flanges of the member are free and provided with openings 57. The offsetting portion 58 of the trip arm 25 is seatable between the free flange portions and the openings in the offset portion 58 will receive a pin 58' which also extends through the openings 10 in the trip throwing member 54.

A leaf spring (clearly shown in Figure 6) is denoted by numeral 59 and is anchored at one end to the carrier plate 36, while its free end impinges against the opposite side of the trip throwing member 54.

The bell crank 60 is swingably connected to one of the posts 15 by its heel a, this bell crank 60 being provided at one end with the T-head 61 which fits through the longitudinally extending slot 62 in the free end of the switch lever 12, this switch lever 12 being swingably supported at 63. The coiled extensible spring 64 is interposed between the remaining end of the crank 60 and one of the legs 56 of the trip throwing member 54.

Mounted upon one of the posts 16 is the indicating shutter 65, the same being provided with an arm 66 pivotally connected, as at 67, to the post. Numeral 68 represents an elongated indicator operating arm pivotally connected, as at 69, to the intermediate portion of the arm 66 and provided with a notch 70 at an intermediate point capable of receiving the pintle 71 which projects inwardly from one leg of the switch lever 12. The arm 68, at its free end, is provided with a downturned foot member 72 located within the path of the upwardly swingable trip arm 25. The coiled spring 73 is interposed between the foot end of the arm 68 and one of the posts 16. 40

By referring to Figures 1 and 2, it can be seen that the hood 6 is provided with a small peep opening 74 therein through which the indicator shutter 65 is visible.

It can now be seen that when the switch is manually operated, the entire thermal breaker mechanism, involving the elements in Figures 11, 12, 13, 14, 15 and 17, remain intact in the compact position, as shown in Figure 3, and simply rock with the toggle action of the switch 50 in conjunction with the bell crank 60. For example, when the switch is in closed circuit position, the parts will be as represented in Figure 3, while when the switch is manually in open circuit position, the mechanism will be as shown in Figure 7. However, when there is an overload or a short circuit and the thermal element 47 flexes so as to press its head 46 against the offset head 45 on the trigger arm 38, the arm 38 is moved inwardly toward the mechanism, thus moving the shoulder 44 of the trigger arm away from over the trip arm 25. The tension of the spring 59 now throws the trip throwing member 54 upwardly and this action rocks the trip arm 25 slightly so that the latch 23 is disengaged from the opening 22 in the contact plate 20, thus freeing the contact plate 20 so that the spring 29 will pull the same downwardly to the open circuit position shown in Figure 4. The trip arm 25 will continue upwardly and strike against the foot 72 of the indicator operating arm 68, resulting in the disengagement of this arm 68 from the pintle 71 so that the spring 73 can pull the arm over the pin to the position shown in Figure 6, 75

thus displaying the word "Re-set" through the sight opening 74 in the hood 6.

By simply moving the lever 12 from the "On" to the "Off" position, a downward pull is exerted by the spring 73 on the trip throwing member 54 which snaps the trip arm 25 downwardly so that the free end thereof will again catch under the shoulder 44. Thus the thermal circuit breaker is again re-set automatically for operation.

- 10 A slightly modified form of the invention is disclosed in Figures 18 to 21, inclusive. In this form of the invention, a casing 6^a is employed. This casing has a cover plate A provided with the switch lever slot 10^a therein through which 15 the switch lever handle 11 protrudes. The cover plate A has a sight opening of any desired configuration therein and this is denoted by numeral 74^a behind which may be placed a suitable light diffusing glass or the like. This opening 74^a is 20 over the compartment B which is separated from the mechanism compartment by the partition C. In the compartment B is a lamp 80, one side of which is connected by the jumper 81 to one side of the line 82. The other side of the line is connected through the switch mechanism by way 25 of the thermostatic element 41. An additional binding post 83 is provided on the base 5 and from this extends the jumper 84 to connect to the opposite side of the lamp 80. In addition to the 30 lamp 80 and its electrical connections above described, a contact, such as is shown in Figure 21, is employed in lieu of the indicator operating arm shown in Figure 17 and the indicator element 65 of the preferred form of the invention.
- 35 The contact shown in Figure 21 consists of the small base plate 85 secured first by the binding post 83 and from this extends an upstanding post

86. Extending laterally from this post 86 is the arm 87 and at its free end is a depending inclined spring contact member 88 located within the path of the trip arm 25. Obviously, when the trip arm goes up as a result of the releasement of the thermal circuit breaker mechanism and strikes the contact 88, while the contacts 18-19 separate, current will be taken off of the line side of the switch and supplied to the lamp 80 so as to indicate that the thermal breaker has operated. 10

While the foregoing specification sets forth the invention in specific terms, it is to be understood that numerous changes in the shape, size and materials may be resorted to without departing from the spirit and scope of the invention as 15 claimed hereinafter.

Having described the invention, what is claimed as new is:—

A switch of the class described, comprising a base, a pair of spaced upstanding posts, a second 20 pair of upstanding posts spaced from said first named posts, and obliquely disposed stationary electrical contact on said base, a swingable plate pivotally mounted at one end to said second named posts and having an electrical contact 25 thereon adapted to cooperate with the stationary electrical contact in opening and closing an electrical circuit, resilient means normally urging the plate in a direction to open the electrical contacts, a switch arm for maintaining the plate in a position for opening said electrical contact, a resilient trigger arm for actuating said switch arm, a thermal element for actuating said trigger arm, and means pivotally mounted on said first named posts for manually actuating said swingable 30 plate. 35

JOSEPH A. O'BRIEN.
